UNITED STATES PATENT OFFICE.

WILLIAM OVERFIELD BUNNELL AND QUINCY ADAMS GATES, OF WILKES-BARRE,
PENNSYLVANIA.

RIGID-BLOCK CAR-REPLACER.

1,162,334.

Specification of Letters Patent. Patented Nov. 30, 1915.

Application filed June 26, 1915. Serial No. 36,451.

To all whom it may concern:

Be it known that we, WILLIAM OVERFIELD BUNNELL and QUINCY ADAMS GATES, citizens of the United States, residing at 5 Wilkes-Barre, in the county of Luzerne and State of Pennsylvania, have invented certain new and useful Improvements in Rigid-Block Car-Replacers, of which the following is a specification.

This invention relates to improvements in 10 railways, and more specifically to rigid block car-replacers.

The object of our invention is to provide a car-replacer of such a shape and construction that it will readily seat adjacent a railway rail in such manner that a derailed car 15 may be run thereupon and guided back upon the track.

Our replacer is so constructed as to be 20 used either inside or outside of the rails, or for moving a car either forwardly or backwardly in order to guide it back upon the rail.

Furthermore, our device is simple in construction, durable in that it has no movable 25 parts to become disarranged or broken, and is extremely efficient in operation.

Other objects of this invention not at this 30 time more particularly enumerated, will be clearly understood from the detailed description and drawings forming a part of this specification.

Furthermore, this invention consists in the novel arrangement and combination of 35 parts more particularly described in the following specification and embodied in the claims appended hereunto and forming a part of this application.

Referring now to the drawings, which 40 are merely illustrative of our invention, Figure 1 is a top plan view of our device illustrating its relative position to the top of a rail, said rail being shown in dotted lines. Fig. 2 is a cross sectional view 45 thereof taken on the line 2-2 of Fig. 1.

Referring further to the drawings, wherein similar reference characters designate similar parts throughout the respective views, 1 designates a metallic block body 50 portion of our device which is formed with a vertical face 2 substantially triangular in outline, a horizontal base 3 one side of which is adapted to conform to one side of the base of a rail as shown in Fig. 2, the top 4 being 55 inclined in opposite directions from a point

near the center of the upper portion of said face 2 and flaring outwardly to a point coincident with the outer edge of said base 3. Oppositely disposed angular faces 5 are formed from the outer edges of both inclined faces of said top extending downwardly and outwardly to a point of meeting centrally of said body portion. A plurality of grooves 6 are formed within the faces of said top, said grooves being flared 60 at 7 at the lower ends thereof and running into a single groove 8 at the upper ends thereof. A boss 9, substantially half ovoid in shape is formed integrally upon the uppermost portion of said body portion and 65 centrally thereof, said boss being adapted to project slightly outwardly with respect to the vertical face 2. Said vertical face is of such a configuration along the length thereof as to conform with the maximum curvature permissible in a railway. A plurality 70 of sharp projections 3^a are formed upon the base 3 adjacent the outer edges. A handle 3^b is formed upon the angular faces 5 near the lower edge thereof.

A clamp 10, formed with a hook 11 upon one end and an upturned arm 12 upon the other end thereof, is provided with a cam lever 13 pivotally mounted upon the end of 75 said upturned arm 12.

In operation, our car-replacer is placed with the vertical face thereof adjacent the side of a rail 14, and with one of the inclined tops thereof facing the wheels of a derailed car. The clamp 10 is then hooked upon the base of said rail opposite the car replacer in such position that the cam lever will engage with the angular face 5 near the lower end thereof, whereby said car-replacer will be retained in fixed position with respect to 80 said rail 14. As the wheels of the derailed car are brought in contact with the lower edge of the inclined top 4 they will be guided upon the car-replacer by means of one of the flared ends 7 of the groove 6, thence to the groove 6 connected with the said flared end and to the single groove 8 at the upper portion of the replacer. The boss 9 is of such shape and is so disposed with respect to the head of the rail 14 that the wheel will be forced over and upon said rail. 85

The utility, adaptability, and advantages of our improved form of rigid block car-replacers being obvious, it is unnecessary to further enlarge upon the same herein. 90 100 105 110

Having now described and pointed out the new and useful features of our invention, we do not limit ourselves to the shape of certain parts where the shape is not essential, nor do we restrict ourselves to the exact details of construction shown and described, but mean and intend to claim all equivalents and variations thereof not departing in principle from our invention, and falling 12 within the purview of the appended claims.

What we claim as our invention and desire to secure by Letters Patent is:

1. A car-replacer consisting of a metallic block, said block being formed with a vertical face substantially triangular in outline and a plurality of angular flaring faces extending from the apex to the base of said block, the oppositely extending faces being provided with a plurality of grooves adapted to receive the flange of a car wheel, and a substantially half-ovoid boss formed integral with the apex of said block.

2. A car-replacer consisting of a metallic body portion, said body portion being formed with a vertical face substantially triangular in outline and a plurality of angular flaring faces extending from the apex to the base of said body portion, the oppo-

sitely extending faces being provided with a plurality of grooves adapted to receive the flange of a car wheel, a substantially half-ovoid boss formed integral with the apex of said body portion, and a plurality of angular projections formed upon the under face of said body portion.

3. A car-replacer consisting of a metallic body portion, said body portion being formed with a vertical face substantially triangular in outline and a plurality of angular flaring faces extending from the apex to the base of said body portion, the oppositely extending faces being provided with a plurality of grooves adapted to receive the flange of a car wheel, a substantially half-ovoid boss formed integral with the apex of said body portion, a plurality of angular projections formed upon the under face of said body portion, and a clamp adapted to engage with said replacer and the base of a rail to retain the replacer in close proximity to said rail.

In testimony whereof we affix our signatures hereto.

WILLIAM OVERFIELD BUNNELL.
QUINCY ADAMS GATES.
